UNITED STATES PATENT OFFICE.

PETER L. BROCKLEBANK, OF SARATOGA SPRINGS, NEW YORK.

WINDOW-GRATING.

SPECIFICATION forming part of Letters Patent No. 341,313, dated May 4, 1886.

Application filed December 28, 1885. Serial No. 186,873. (No model.)

To all whom it may concern:

Be it known that I, PETER L. BROCKLEBANK, a citizen of the United States, residing at Saratoga Springs, in the county of Saratoga and State of New York, have invented certain new and useful Improvements in Window-Gratings; and I do hereby declare the following to be a full, clear, and exact description of the invention, such as will enable others skilled in the art to which it appertains to make and use the same.

My invention relates to window-gratings and the object thereof is to provide a grating, the parts of which may be advanced toward each other or retracted across the path of the window-sash, and which when not in use may be entirely inclosed in boxes formed in the sides of the sash-frame.

In the accompanying drawings, in which corresponding parts are designated by similar letters, Figure 1 represents a window having my improvement applied thereto. Fig. 2 represents the grating detached from the sash-frame; and Fig. 3 illustrates the grating as it appears when in a closed position.

The sash-casing may be provided with an inside, outside, and parting bead forming slides between which the sash-stiles travel in the usual manner, and on each side thereof are formed boxes or pockets A, entirely within the sash-frame for the reception of the grating. Vertical slides B are cut through each side of the sash-frame, through which the gratings C and C' are drawn. These gratings consist of diagonal iron bars pivoted together on the principle of lazy-tongs and attached by pivot-bolts to the upright bars D and E. Each of the upright bars D and E is provided with lugs a, a', and b. The lazy-tongs are directly pivoted to the central lug, but are connected by means of straps d'd' to the upper and lower lugs, a'a', these straps being pivoted to the lugs, and also to the bars of the lazy-tongs in

such a manner as to allow for the upward and downward play thereof.

The bar E is bolted or secured within the box or pocket in the side of the sash-frame; but the bar D may be drawn in or out with facility.

It will be obvious that when the window-sash is raised the lazy-tongs may be distended until the bars D meet each other, and that when in this position the gratings may be locked or secured together by any suitable lock or fastening. When thus distended, spaces will be formed above and below the lazy-tongs for the admission of air and light, while at the same time the window will be protected from intruders. The bars D will also form a support and fastening for the sash which has been raised.

Having thus described my invention, I claim and desire to secure by Letters Patent—

1. The combination of a sash-frame, gratings capable of moving in the path of the sash and of being retracted entirely within the sash-frame, and sides of the sash-frame, through which the gratings travel, as and for the purpose described.

2. The combination of a sash-frame, having in each of its sides boxes or pockets, and gratings constructed of idle-tongs capable of being extended without and retracted within the boxes in the sides of the sash-casing, as and for the purpose described.

3. The combination, with a sash-frame having boxes in its sides, of the idle-tongs C, upright bars D and E, lugs a a' b, and straps d, as and for the purpose described.

In testimony whereof I affix my signature in presence of two witnesses.

PETER L. BROCKLEBANK.
